UNITED STATES PATENT OFFICE.

LOUIS MAYER, OF KAUKAUNA, WISCONSIN, ASSIGNOR TO KAUKAUNA MACHINE WORKS, OF KAUKAUNA, WISCONSIN, A CORPORATION OF WISCONSIN.

THISTLE ERADICATOR.

Application filed February 24, 1920. Serial No. 361,046.

To all whom it may concern:

Be it known that I, LOUIS MAYER, a citizen of the United States, and resident of Kaukauna, in the county of Outagamie and 5 State of Wisconsin, have invented new and useful Improvements in Thistle Eradicators, of which the following is a description, reference being had to the accompanying drawings, which are a part of this specification.

10 The present invention relates to certain new and useful improvements in thistle eradicator and has for one of its objects to provide a thistle eradicator which will be of comparatively light but durable construction, and efficient in operation.

Another object of this invention is to provide means for readily adjusting the distance between the thistle removing member and the ground which will comprise a few parts 20 but which will be of efficient construction.

A further object of my invention is to provide improved means for operatively connecting and disconnecting the thistle eradicator drive gear from the main drive gear.

25 With the above and other objects in view which will appear as the description proceeds, my invention resides in the novel construction, combination and arrangement of parts substantially as hereinafter described 30 and more particularly defined by the appended claims, it being understood that such changes in the precise embodiment of the herein disclosed invention may be made as come within the scope of the claims.

35 In the accompanying drawing I have illustrated one complete example of the physical embodiment of my invention constructed according to the best mode I have so far devised for the practical application of the 40 principles thereof, and in which:

Figure 1 is a side elevation of my improved machine, the wheel nearest the observer being removed, and parts being broken away to more clearly illustrate structural details.

45 Figure 2 is an enlarged fragmentary perspective view illustrating the means I employ for adjusting the elevation of the comb members and for moving the carrying side arms horizontally to engage and disengage the comb driving gear from the main gear, said view having parts broken away and in section.

50 Figure 3 is a fragmentary perspective view of the means I employ for maintaining

the comb gear and the drive gear in either operative or inoperative engagement, and

Figure 4 is a detail sectional view through one of the comb carrying side arms and bearing members, said view being taken on 60 the line 4—4 of Figure 2.

My invention may be said to broadly consist of wheeled means having a comb carrying frame mounted thereon, gear means for drivingly connecting the comb carried by 65 said frame with a driven wheel, means for moving the side members forming said frame horizontally to connect and disconnect said gears, comb cleaning members having means for positively moving the same along 70 the comb surface once every revolution to remove foreign matter therefrom, and means for adjusting the elevation of the outer end of said frame to position the comb members with respect to the ground.

75 My device is supported by means of a pair of wheels 10 revolvably journaled on shaft spindles 11 carried by a main axle member 12 having thills 13 secured thereto in any desired manner. The thills 13 are connected 80 by means of a transverse member 14 forming, with the axle 12, a frame on which is mounted a driver's seat 15. Journaled on each spindle 11 inward of the adjacent wheel 10 is a bearing block 16 having an elongated 85 rearwardly extending support 16' slidably secured to a side arm 17, forming a part of the comb carrying frame, by means of a securing member 18.

90 The side arms 17 are each provided with two horizontally aligned elongated apertures 19 and 20 through which pass the axle spindle 11 and the securing member 18 respectively.

95 This structure permits the outer free end 21 of each side arm 17 to be moved toward or away from the axle spindle 11, and this horizontal movement of the side arm 17 is controlled by means of a rod or shaft 22 journaled in bearing brackets 23 carried by 100 the axle 12. Crank arms 24 are formed on the ends of said shaft and are engaged in curved recesses 25 formed in that portion of the side arms forward of the axle spindle 11. The shaft 22 is rotated by means of a 105 hand lever 26 and is adapted to be held in either one of two adjustments, one with the ends 21 of the side arms 17 spaced from the axle, and vice versa, by means of a bracket member 27 provided with notches 28 in 110

which the lever 26 is selectively engaged. This horizontal movement, or extension, of the side arms 17 is effective to engage and disengage the driving gears to be later described.

Secured to each side arm 17 near its outer free end 21 is a member 29 in which is journaled the adjacent end of a shaft 30. Said shaft has secured to its portion intermediate the members 29 reel heads 31 carrying comb members 32. The comb members and reel heads may be of any desired construction and the comb members are preferably provided with cleaning means including cleaner bars 33 carried by operating levers 34 pivotally carried by the reel heads and operable once every complete revolution of the adjacent comb to sweep the comb and remove foreign matter therefrom.

The shaft 30, and with it the reel heads and combs, is adapted to be rotated from the wheels 10 and has secured to each end thereof a gear wheel 35 provided with an internal differential mechanism (not shown) connecting the same with the shaft. The gear wheel 35 is engageable with a main drive gear 36 rigid with the adjacent wheel 10, and said gears are movable to engaging and disengaging positions by the horizontal moving of the side arms 17. With the lever 26 in the position depicted in Figures 1 and 3, the gears 35 and 36 will be in mesh and when the wheels 10 are rotated, the combs 32 will be rotated in the direction of the arrow in Figure 1, and when the lever 26 is engaged in the other notch 28, the gears will be disengaged and the revolution of the gears 36 will not impart any movement to the combs. As before stated the gears 35 contain differential means for connecting the same to the shaft 30 whereby the turning of the machine, where one wheel 10 revolves faster than the other wheel 10, will not in any manner injure the device.

The combs 32 are adapted to be adjusted vertically to arrange them at various heights with respect to the ground by means of a tubular shaft 37 journaled in bearings 38 carried by the axle 12 and having secured in each end thereof as at 39 a rearwardly extending crank arm 40. The extreme outer ends of the crank arms 40 are pivotally connected with the side members 17 by means of links 41 pivotally connected as at 42 to the crank arms 40 and pivotally connected as at 43 to the side arms 17.

The shaft 38 is adapted to be rotated by means of a hand crank 44 operating a worm gear 45 secured to the lower end thereof and in mesh with a segmental gear 46 fixed to the shaft 37. The lower end of the hand crank 44 carrying the worm gear 45 is pivoted in a bracket member 47 carried by the frame formed by the inner ends of the thills, the axle 12 and the member 14. As

will be obvious, when the outer ends of the cranks 40 are raised the distance between the combs 32 and the ground will be increased and when the cranks are lowered the distance will be decreased.

70

As best shown in Figure 1, a suitable guard or shield 48 is carried by the frame formed by the inner ends of the thills, the axle and the member 14 and extends upwardly and outwardly therefrom rearwardly of the driver seat to protect the driver from the clogs of earth, etc., apt to be thrown upwardly by the thistles or the like caught by said comb members.

75

What I claim as my invention is:

80

1. A machine of the class described, comprising a supporting axle, supporting wheels carried thereby, side arm members having their inner ends connected with the axle and their outer ends free, a comb member mounted between the free ends of said side arm members, and means for simultaneously swinging said side arm members to adjust the relation of the comb member with respect to the ground, operating means for said comb members and means for longitudinally moving said arm members for disconnecting said operating means.

85

2. A machine of the class described, comprising a supporting axle, supporting wheels carried thereby, side arm members having their inner ends connected with the axle and their outer ends free, said side arm members being extensible to adjust the distance between the outer free ends thereof and said axle, a shaft journaled in the free ends of said side arm members and connecting the same, a comb member carried by said shaft, a drive connection between one of the supporting wheels and said shaft, and means for extending said side arm members to disengage said drive connection and render the comb carrying shaft inoperative.

95

3. A machine of the class described, comprising a supporting axle, supporting wheels mounted on said axle, side arm members having their inner ends adjustably supported by said axle and their outer ends free, a comb member revolvably mounted between the free ends of said side arm members, a drive connection between said comb member and one of the supporting wheels, and means for adjusting the side arm members to vary the distance between their outer free ends and the supporting axle to connect and disconnect said drive connection.

100

4. A machine of the class described, comprising a supporting axle, supporting wheels mounted on said axle, side arm members having their inner ends longitudinally slidably mounted upon said axle and their outer ends free, a comb member revolvably mounted between the free ends of

110

115

120

125

130

- said side arm members, a drive connection between said comb members and one of the supporting wheels, and means for sliding said side arm members longitudinally to 5 adjust the distance between the free ends thereof and the supporting axle to connect and disconnect said drive connection.
5. A machine of the class described, comprising a frame, supporting wheels for 10 the frame, a side arm member extensibly carried by the frame and having its outer end free, a comb member revolubly carried by the outer free end of said side arm member, a drive connection between said 15 comb member and one of the supporting wheels, and means for extending the side arm member to vary the distance between the free ends thereof and the supporting frame to disconnect said drive connection.
- 20 6. A machine of the class described, comprising a supporting axle, supporting wheels therefor, a side arm member provided with an elongated recess through which the axle passes, a crank member having 25 its inner end journaled on said axle juxtaposed to said side arm member, fastening means carried by the outer end of said crank arm and slidably engaging a longitudinally extending slot in said side arm 30 member, the outer end of said side arm member being free, a comb member revolubly carried by the outer free end of said
- side arm member, a drive connection between one of the supporting wheels and said comb member, and means for sliding 35 said side arm member horizontally to vary the distance between the outer free end thereof and said supporting axle to disconnect and connect said drive connection, said sliding movement being limited by said 40 elongated recess and slot.
7. A machine of the class described, comprising an axle, supporting wheels mounted thereon, a side arm member having a horizontally extending elongated recess therein adjacent its inner end and through which said axle passes, the outer end of said side arm member being free, a comb member revolubly carried by the outer free end of said side arm member, 45 a drive connection between said comb member and one of the supporting wheels, the portion of the inner end of said side arm member inwardly of the axle having an arcuate slot therein, a crank arm engageable in said slot, and means for rotating 50 said crank arm to extend and retract said side arm member, to connect and disconnect the drive connection between said comb member and the supporting wheel. 55

In testimony whereof, I affix my signature.

LOUIS MAYER.
